UNITED STATES PATENT OFFICE

2,691,695

INSULATING SUPPORT FOR ELECTRICAL WIRES

Oscar L. Hanson, Bruce, and Oscar S. Steen,
Brookings, S. Dak.

Application June 24, 1949, Serial No. 101,058

3 Claims. (Cl. 174—157)

1

This invention relates to electrical insulators and especially to insulating devices designed to support wires that conduct electricity.

More particularly, the present invention is concerned with insulators arranged in line at a series of spaced points to support one or more electrically charged wires. As a specific example, one may mention the electric fence commonly used on ranches or ranges to prevent livestock from crossing borders and where the line may frequently be broken down or the insulators may require replacement.

It is the primary object of the present invention to devise an improved insulator to which a freely strung wire may be conveniently attached or slung. In this connection it is an object to provide an insulating body (one or more parts) and a mounting device therefor having a common clamping means for securing the device to a support and for holding a conducting wire within or upon the insulating body. Hereinafter, and in the claims, "an insulator" is intended to refer to a complete insulating device with any associated parts for mounting it upon a permanent support.

It is a further object to devise an insulator comprising an adjustable clamp to fit supports of variable shapes and sizes such, for example, as fence posts of L, T and U cross sectional shapes.

Another object of this invention is to provide an insulator having a two-part body, one part grooved for reception of a wire and the other part adjustable to permit easy insertion and removal of the wire. In this connection, it is an important object to pivotally interconnect the two parts on an off-center pivot, with the groove also off-center, for purposes to appear later.

The term "wire" is intended to mean whether a bare wire or a conductor covered with insulating material.

The foregoing and further objects of this invention should clearly appear from a study of the following detailed description when taken in conjunction with the accompanying drawings, wherein:

Fig. 1 is a front elevational view of a preferred embodiment as it might be designed, for example, for attachment to a fence post;

Fig. 2 shows the same device in side elevation and partially in cross section as seen on line 2—2 of Fig. 1;

Fig. 3, viewed as in Fig. 1, illustrates the manner in which a part of the insulating body is adjusted to facilitate insertion or removal of a wire;

Fig. 4 is a perspective view of the clamping

2

means with the entire insulating body removed therefrom;

Fig. 5, in a view corresponding to Fig. 4, shows a slightly modified form of the invention; and

Fig. 6, further illustrating the embodiment of Fig. 5, represents a cross section taken substantially on the plane that divides the two-part insulating body.

With continued reference to the drawing, and 10 first to Figs. 1—4 only, there is shown for support of an insulating body, a clamp comprising two axially adjustable parts 8 and 9 having, respectively, winged or hooked ends 10, 12, designed to engage and receive two edges of a supporting member such, for example, as a steel fence post. The part 9 has a stem 13 secured thereto, preferably by welding as at 14, and this stem extends through a longitudinal slot 15 in the part 8. In the form being described, the stem is cylindrical 15 in cross section and hence the parts 8 and 9 may be oscillatably as well as linearly adjusted.

The free end 16 of the stem 13 is externally threaded to receive a clamping element which may take the form of an internally threaded wing 25 nut 17. Between this nut and the part 8 there is interposed a pair of wire-holding and insulating elements 18, 19, formed of porcelain or any other suitable material and constructed as follows:

30 The elements 18 and 19 may be of any desired cross-sectional shape but preferably are cylindrical, and they are apertured longitudinally and eccentrically to freely receive the stem 13. In its outward face the element 18 has also a transverse groove 20, also eccentric but in a zone opposite the center line from the pin 13. This groove 20 is provided for reception of a conducting wire (not shown) which may be either secured or loosely slung therein when the nut 17 is tightened.

40 Tightening of the nut 17 serves to fasten the clamp 8, 9 to a post or other support while simultaneously serving to trap the wire within the groove 20 by pressing the elements 18, 19 together.

45 Offsetting the groove 20 and the pin 13 at opposite sides of the center line serves two purposes. First, it affords a maximum insulating distance between the pin and the conducting wire to be suspended. Secondly, and more important, it 50 facilitates connection of the wire to the insulator for, as seen in Fig. 3 the element 19 may be oscillated to hang downwardly and thus expose the groove, after which (upon nimbly pushing the wire into slung position) the element 19 may be 55 swung to the position of Figs. 1 and 2 prior to

tightening of the nut 17. It should be appreciated that the relationship between the groove and the pin may be reversed (see Fig. 6) or otherwise altered within the scope of the invention.

As seen in the modification illustrated in Figs. 5 and 6, a pin 130 that is square or otherwise non-rotatably shaped may extend freely through a complementary hole 200 in an insulating element 180 that corresponds to the element 18 of Figs. 1-3. By this provision the clamp members 8 and 9 are limited to axial movement and the groove 20 is held at any predetermined angle to the axis of the clamp. Also, as noted above, the groove may be below instead of above the pin, thus requiring an upward instead of a downward oscillation of the element 19 to permit insertion of the undisclosed conducting wire.

The operational use of the device ought now to be clear. It should be understood that various changes in design may be made within the scope of the present invention. Therefore, as is customary, it is desired that the appended claims be given a reasonable liberal interpretation in the light of the prior art.

What is claimed is:

1. In an insulating device, a single interconnection pin, fixedly mounted, an insulating part non-rotatably supported by said pin, a second insulating part oscillatable upon said pin in juxtaposition to said first mentioned part, normally on a line below its center of gravity, one of said parts having a straight groove facing the other

and of a depth to completely receive a portion of a suspended conducting wire.

2. In claim 1, said groove being formed entirely in the first mentioned insulating part.

5 3. In an insulating device, a support comprising a stationary element carrying a fixed pin, said pin having a non-cylindrical section to which is mated a nonrotatable insulating element, said pin also having an extension upon which there is 10 mounted in close juxtaposition a freely oscillatable insulating element, said elements providing in one position a channel for complete retention of a conductive wire, and readily manipulatable means on the extreme end of said extension for 15 locking and unlocking said elements against and from relative rotation.
